UNITED STATES PATENT OFFICE.

LEIF N. OLSEN, OF BROOKLYN, NEW YORK.

COMBINED CIGARETTE AND MATCH CASE.

Application filed July 9, 1923. Serial No. 650,334.

To all whom it may concern:

Be it known that I, LEIF N. OLSEN, a citizen of the United States, and a resident of Brooklyn, in the county of Kings and State 5 of New York, have invented certain new and useful Improvements in Combined Cigarette and Match Cases, of which the following is a specification.

The invention relates to a combined cigarette and match case adapted to receive and accommodate a full package of cigarettes in the original wrapper as well as a book of matches for use therewith, the matches, for example, being of the ordinary safety type 15 with igniting strip attached thereto.

The invention has for its object a protective casing of this character which shall be compact and occupy as little space as possible, and which shall, moreover, be of durable 20 construction and material to adequately protect the contents, and so arranged that a book of matches or pack of cigarettes may readily be inserted when it becomes necessary to replenish the supply of same. A further object of the invention consists in the arrangement whereby the matches normally 25 are suitably covered and protected, when the box is closed, but wherein the igniting surface of the book will remain exposed thru the holding portion for the book as well as thru a lid or cover provided for the case.

The nature of the invention, however, will best be understood when described in connection with the accompanying drawings, in 30 which—

Fig. 1 is a front elevation of the improved cigarette and match case.

Fig. 2 is a side elevation thereof; and Fig. 3 is a plan view.

Fig. 4 is a vertical section taken on the line 4—4, Fig. 1.

Fig. 5 is a perspective view of the case with the cover swung open.

Similar characters of reference designate 45 corresponding parts thruout the several views.

Referring to the drawings, 10 designates a long thin container or receptacle of flat back and front walls and curved sides and 50 of the proper dimensions to receive with a snug fit a full package of cigarettes in the original wrapper; and this casing may be of any suitable material, preferably of thin light sheet metal, as aluminum. It will be 55 understood that more expensive material may be employed for this purpose and that a

casing may be embellished as desired. The case may be drawn or pressed to shape; and there is hingedly secured at the top edge of the back portion thereof a cover 11 for the 60 top for closing securely the mouth of the case. The cover 11, furthermore, has integrally formed therewith a flap member 13, also of metal, and adapted to extend downwardly over the front of the case when the 65 top is in the closed position, as shown in Fig. 1.

There is provided, moreover, in any suitable manner at the front wall portion of the casing, an open receptacle or pocket 15 having side walls 16 and an intermediate turned-up bottom member 17 in the nature of a resilient tongue into which is adapted to be slid the bottom portion of a book of matches 18. As is usual, the bottom portion of the 70 book of matches carries an igniting strip 19; and the resilient tongue is cut away to provide a slot or opening 20 thru which the igniting strip will be exposed so that a match 75 may be struck thereon without the necessity of withdrawing the book from its holder.

Moreover, the flap 13 is adapted to fit over and to close substantially the match holder; and at its lower end is also cut away to provide a slot or opening 21 registering with 80 the slot 20 so that even when the cigarette and match holder case is closed entirely, as indicated in Fig. 1, the igniting surface is still available. The flap is turned over and inwardly at its lowermost edge to fit and 85 lock over the lower end of the match holder which is rounded for this purpose; and a lip 23 extends downwardly and outwardly from the lowermost edge of the flap to afford convenient means for opening the flap which 90 may be swung back to the position indicated in Fig. 5. In this position, the interior of the case 10 is exposed so that a cigarette or cigarettes may be readily withdrawn, the forward upper edge of the case having a 95 curved notch 24 to facilitate withdrawal. It will be noted, also, that the matches are exposed and ready for use when the flap is in this position; and when a new book is required, it is necessary merely to slide out the 100 stub of the old book and replenish same with a new supply of matches.

The combined cigarette and match case hereinbefore described is of such proportions as to fit conveniently in a pocket without undue bulging; and affords substantial 105 protection to the contents which are con-

sealed thereby so long as the box is closed, though providing an igniting or striking surface for a match. The box may thus be safely and readily carried about while keeping the contents in proper condition.

I claim:—

A combined cigarette and match case, comprising an open casing for cigarettes, an open match receptacle on the front wall thereof and having at the bottom a resilient up-turned tongue to retain a book of matches provided with an igniting surface, said tongue being provided with an opening to expose the igniting surface of a book of matches when the same is inserted in the re-

ceptacle, a cover hinged to the upper edge of the rear wall of the casing, extending over the top to close the mouth thereof and having a depending flap extending over the front wall and the match receptacle to close the latter, the lower end of the flap being turned inwardly to lock over the lower end of the tongue of the receptacle and having an opening adapted to register, when thus locked, with the opening in the said tongue.

Signed at New York, in the county of New York and State of New York, this 6th day of July A. D. 1923.

LEIF N. OLSEN.
